(57) **CLAIM**

The ornamental design for a dental unit, as shown and described.

DESCRIPTION

FIG. 1 is a perspective view of a dental unit;

FIG. 2 is a front plan view thereof;

FIG. 3 is a first side plan view thereof;

FIG. 4 is a rear plan view thereof;

FIG. 5 is the other side plan view thereof;

FIG. 6 is a top end view thereof; and,

FIG. 7 is a bottom end view thereof.

It will be understood that the broken lines presented in the drawings are for illustration only, and do not form a part of the claimed design.
